UNITED STATES PATENT OFFICE.

ROBERT SILVER, OF KNIGHTSTOWN, INDIANA.

FUNERAL CAR.

Application filed March 10, 1927. Serial No. 174,354.

My invention relates to a side loading funeral car or hearse, the object being to provide a vehicle of this character which may be readily loaded from either side and in which means are provided for supporting the casket arranged in a manner to guide the casket in place centrally within the body of the vehicle in an easy and convenient manner, all as will be hereinafter more fully described and claimed.

Referring to the accompanying drawings which are made a part hereof and on which similar reference characters indicate similar parts,

15 Figure 1 is a perspective view illustrating one application of my invention,

Figure 2, a horizontal section,

Figure 3, a fragmentary detail perspective,

20 Figure 4, a section on the line 4—4 of Fig. 3, and

Figure 5, a section on the line 5—5 of Fig. 4.

In the drawings reference character 10 indicates a vehicle body of the funeral car type provided with doors 11 and 12 (preferably double doors, as shown) which are mounted by appropriate hinges on the body 10 in a manner to permit them to swing outwardly 25 to provide a clear unobstructed opening or doorway equal to the size of the combined doors. Each side of the body is preferably a duplicate of the other and is provided with such doors in order to afford ready access at either side of the vehicle in loading or unloading. A pair of seats 13 and 14 for driver and attendant, of the basket or collapsible type, are provided at the front of the vehicle. Such seats when collapsed occupy 30 a position so as not to obstruct the doorway at either side of the vehicle.

In Fig. 1, I have shown a casket 15 within the vehicle and in Fig. 2, have illustrated by dotted lines the relative position of the casket as it is being placed in the vehicle.

In order to render the loading and unloading of the casket comparatively simple and easy, I provide one or more rollers 15 disposed at an angle to the longitudinal axis 50 of the vehicle and on each side thereof.

These rollers are preferably adjacent the rear doors 11 and are arranged to cause a casket to swing in line with the vehicle body as it is moved rearwardly when being loaded.

55 In order to further bring the casket into line with the sides of the vehicle or into its

proper longitudinal position, I provide other rollers 16 disposed transversely of the body, which serve when the casket is pushed in over the rollers 15 to receive it and tend to swing it to a position longitudinally of the vehicle. The rollers 15 and 16 are shown in alined pairs, each roller being of appropriate length and spaced apart so that each pair is of a length sufficient to support the width of a full sized casket. As shown one set of inclined rollers 15 are disposed at each side of the vehicle, obviously, however, additional rollers might be provided if desired. Likewise instead of three sets of rollers 16, 60 any other appropriate number may be employed.

To prevent the rubbing and abrasion of the lower adjacent edge of the casket against the sides of the doorway as it is loaded, I 65 provide a rubber covered roller 17 mounted in a bracket 19 in substantially vertical position at the rear corner of each doorway to engage and protect said lower edge and at the same time assist the rollers 15 and 16 70 in guiding the casket to its place. Directly behind each roller 17 is mounted a sliding block 19 against which the opposite corner of the casket is adapted to engage. Said sliding block is provided with an inclined 75 rear inner face and is held in forward position by means of a coiled spring 20. When the corner of the casket engages the sliding block, as it is being loaded, the block will slide rearwardly with the casket and act in 80 conjunction with the rollers to guide the casket into position. As soon as released from such contact coiled spring 20 returns 85 said block to normal position.

In order to hold the casket from moving 90 during the trip in the vehicle, a plurality of pin plates 21 are provided disposed to extend longitudinally one at the front and one at the rear of the vehicle and similar pin plates 22 disposed transversely are provided 95 on each side of the same. The pin plates 21 are provided with longitudinally spaced holes or sockets 23 and the pin plates 22 are provided with transversely spaced sockets 24, the sockets being adapted to receive pins 25 100 for holding the casket in place.

Numerous changes in the details of construction will be apparent and obvious to those skilled in the art without departing from the spirit of my invention, and I, 105 therefore do not limit myself to what is shown in the drawings and described in the

specification, but only as set forth in the appended claims.

Having thus fully described my said invention, what I claim as new and desire to secure by Letters Patent, is:

- 5 1. The combination of a vehicle body, doors mounted in each side of the body and adapted to open to provide an unobstructed opening through which a casket may be loaded, and rollers mounted in the floor of said body and having their axes positioned obliquely with respect to said vehicle body for guiding a casket from an angular to a longitudinal position, and rollers mounted 10 in the floor of the body with their axes transverse of the vehicle for guiding the casket longitudinally of the vehicle, substantially as set forth.
- 15 2. The combination of a vehicle body, a door in the side of the body through which a casket may be loaded, a roller at the rear edge of the doorway adapted to prevent the side of the casket from scraping the edge of the doorway, and a cooperating element at the opposite side of the interior of the vehicle body adapted to be engaged by the corner of the casket and assist in the movement of the casket within the vehicle body, substantially as set forth.
- 20 3. A side loading car comprising a vehicle body, a door at one side of the body adapted to open to provide an unobstructed passageway, a roller in the floor of the vehicle disposed at an angle to the doorway and to the line of access to the vehicle and arranged to guide a casket to slide at an angle across the floor of the vehicle, and another roller disposed transversely of the floor of the vehicle rearwardly of the inclined roller and adapted to act in conjunction with the first roller for guiding an object in a direction longitudinally of the vehicle, substantially as set forth.
- 25 4. A side loading car comprising a vehicle body, a door at one side of the body adapted to open to provide an unobstructed passageway, a roller in the floor of the vehicle disposed at an angle to the doorway and to the line of access to the vehicle and arranged to guide a casket to slide at an angle across the floor of the vehicle, another roller disposed transversely of the floor of the vehicle rearwardly of the inclined roller and adapted to act in conjunction with the first roller for guiding an object in a direction longitudinally of the vehicle, and a slide adjacent the doorway arranged to con-

tact with the end of the casket and assist in guiding it to position, substantially as set forth.

60

5. A side loading car comprising a vehicle body, a door at one side of the body adapted to open to provide an unobstructed passageway, a roller in the floor of the vehicle disposed at an angle to the doorway and to the line of access to the vehicle and arranged to guide a casket to slide at an angle across the floor of the vehicle, another roller disposed transversely of the floor of the vehicle rearwardly of the inclined roller and adapted to act in conjunction with the first roller for guiding an object in a direction longitudinally of the vehicle, and anti-friction rollers on opposite sides of the vehicle body, substantially as set forth.

75

6. A side loading funeral car comprising a vehicle having doors at the side of the same and adapted to open to provide an unobstructed doorway, a roller on each side of the floor of the vehicle disposed at an angle to the longitudinal axis of the same for guiding a casket into the vehicle, and a roller mounted transversely of said last mentioned rollers for guiding the casket longitudinally of the vehicle, substantially as set forth.

80

7. A funeral car comprising a vehicle body with side doors, rollers disposed in the bottom of said vehicle body at an angle to its longitudinal dimension, slides mounted in the vehicle body adjacent the rear edge of each doorway and in position to receive contact of the end of the casket when being loaded from the opposite side and assist in guiding said casket into a longitudinal position, and means for holding said casket from moving after being loaded, substantially as set forth.

85

8. A funeral car comprising a vehicle body with doors in its opposite sides, a series of rollers appropriately mounted in the floor of said vehicle body, part of said rollers adjacent the doors being disposed at an angle to the side of the car and other rollers behind said angularly disposed rollers being disposed transversely of the car, and anti-friction means adjacent the rear edges of the doorways for assisting in the guiding of a casket to position in the vehicle body, substantially as set forth.

90

In witness whereof, I have hereunto set my hand and seal at Knightstown, Indiana, this 7th day of March, A. D. nineteen hundred and twenty-seven.

100

ROBERT SILVER.
